Filed Dec. 10, 1963, Ser. No. 77,737

Term of patent 14 years

(Cl. D37—1)

FIG. 1

FIG. 2

FIG. 3

FIG. 4

FIG. 5

FIGURE 1 is a perspective view of a portable power-operated sander embodying my new design;

FIGURE 2 is a side elevational view thereof drawn to a slightly increased scale and taken from the side which is opposite from that illustrated in FIGURE 1;

FIGURE 3 is a top plan view drawn to the scale of FIGURE 2;

FIGURE 4 is a front elevational view drawn to the scale of FIGURE 2; and

FIGURE 5 is a rear elevational view to the scale of FIGURE 2.

The characteristic features of my design reside in the specific configuration of the front handgrip in combination with the motor and base housings as shown.

I claim:

The ornamental design for a portable power-operated sander, as shown and described.
